GARMENT PRESS RETAINER

William L. Payne, Culver City, Calif.

Application May 17, 1949, Serial No. 93,744

2 Claims. (Cl. 2—243)

1

This invention relates to means for holding the pressed creases on garments, such as trousers, coats and the like, and particularly to garment press retainers which I prefer to term "Perma-Press."

The main object of my invention is to apply means to a garment which will retain the pressed creases in pristine condition while being wholly concealed and unobtrusive in use.

Another object is to provide a garment with a series of transversely-disposed retaining links of resilient and elastic material spaced apart and attached at the ends thereof to the inner opposite sides of the garment and internally bridging the crease to be maintained.

A further object is to provide an initial support in the form of a backing strip for holding the elastic retaining links in place when applying them to a garment, as well as for dispensing them to a user.

It is also an object to have such elastic retaining links of such nature, arrangement, form and size that a garment equipped therewith in no way reveals any bulge or irregularity in form or suffers any disadvantage from the presence of the links within the same.

A practical object is, of course, to have such press or crease-retaining means which may be made and sold at a very reasonable figure to encourage wide distribution thereof.

Other objects and advantages will appear in further detail as the specification proceeds.

In order to facilitate ready comprehension of this invention for a proper appreciation of the salient features thereof, the invention is illustrated on the accompanying drawing forming part hereof, and in which:

Figure 1 is a front elevation of a pair of trousers wherein the creases on the two legs thereof are maintained by garment press retainers made according to the invention and embodying the same in a practical form, a portion of one leg being broken away to disclose part of a series of links of the invention within the garment;

Figure 2 is an enlarged elevation of a backing strip or card upon which a series of resilient retaining links are mounted prior to application to a garment;

Figure 3 is another elevation of the same backing strip or card when folded along the center of the card, as shown in Figure 2, and doubled;

Figure 4 is a transverse section taken on line 4—4 in Figure 2, the section being illustrated on an enlarged scale;

Figure 5 is a fragmentary section of the front

portion of a trouser leg with the backing strip in place and the resilient retaining links thereon being applied to the corresponding inner sides of the trouser leg within the crease or ridge forming the junction of the mentioned sides;

Figure 6 is another fragmentary section of substantially the same portion of the trouser leg after the retaining links have been applied and the backing strip or card removed;

Figure 7 is a perspective view of one of the resilient retaining links of the invention.

Throughout the views, the same reference numerals indicate the same or like parts.

One of the requirements of such garments as coats, trousers and the like is that for maintaining proper appearance they must be smoothly ironed and properly creased, the coats at the front and rear portions of the sleeves thereof, while upon trousers the front and rear portions of each trouser leg should disclose a straight crease. When such garments are worn, however, the crease is rapidly altered and partly disappears, greatly to the detriment of the appearance of the garment involved. I am, of course, aware that many expedients have been resorted to for restoring or maintaining the proper press and creases of trousers and coats, but ordinarily the only manner in which the crease is restored and the garment maintained in properly pressed condition is to have the pressing done over again repeatedly and frequently, even though this subjects the garment to wear and tear, and thus the whole situation presents a problem.

Upon considering this problem, it has occurred to me that means should be available for insertion within the garments involved without in any way impeding the movements of the person wearing them or externally revealing the presence of the mentioned means, the latter being effective to retain the creases on the garments sharp and straight as originally applied thereto. As a result of such consideration, I have succeeded in producing garment press or crease retainers, as will now be more fully described.

Hence, in the practice of my invention, and referring again to the drawing, a pair of trousers, generally indicated at 8, is provided in a conventional manner with a pair of trouser legs 9 and 10 terminating at the bottom, if so desired, in a pair of conventional cuffs 11 and 12. As the view in Figure 1 is a front elevation, the front central portions of both trouser legs are provided with pressed creases 13, 14 extending the entire length of both legs down to and including cuffs 11 and 12, these legs immediately at either side of the

creases forming the converging front side portions 15, 16, 17 and 18, respectively. Naturally, at the rear, both legs 9 and 10 are similarly creased.

In order to maintain the pressed creases on the mentioned trouser legs, upon the inside of each leg immediately within the crease thereon is disposed a series of transversely-arranged elastic natural or artificial rubber or plastic links disposed in a vertical row in such fashion as to bridge the crease itself, as generally indicated at 19, the individual links being indicated by 20. In Figure 1, the links 20 actually shown are disposed adjacent the rear crease 21 of the leg 9, but the front crease 13 is similarly equipped, as will now be discussed in greater detail.

The links 20 are initially mounted on a strip or backing card 22 which is provided with a central fold line 23 and at both sides of the vertical line 23 with a plurality of raised relief sections 24, 24, 25, 25 arranged in vertical series along the two sides 26, 27 of the backing strip 22. Intermediate each pair of projecting relief portions 24 and 25 the backing strip is depressed to form a transverse recess 28. Upon each pair of relief sections 24 and 25 are attached the enlarged disc-shaped ends 29, 30 of a link 20 interconnected by an intermediate narrower strip 31 which bridges the distance between projections 24 and 25 and the intermediate fold line 23 of backing strip 22, while being wholly out of contact with the strip intermediate the projections due to the presence of the rearwardly-impressed recess 28. The backing strip or card 22, aside from having the central fold line 23, is also provided with transverse weakened lines 32, 32 at regular intervals along the vertical length thereof to facilitate tearing off the proper length of backing strip to accommodate the full length of a trouser leg, for example, this backing strip having naturally the requisite number of links 20 spaced along the same to accommodate the length of the trouser leg according to the length of the strip thus torn off.

Preferably, each of the elastic links 20 is under tension so that the intermediate narrow portion 31 thereof readily sinks into the transverse recess 28 when the backing strip 22 is bent along line 23, as best shown in Figure 3. When a proper length of such backing strip has been torn off, the same is introduced into the trouser leg 9, for example, as shown in Figure 5, with the disc-shaped ends 29 and 30 of the links disposed upon the raised portions 24 and 25 in contact with the fabric of the two sides 15 and 16 of leg 9 at both sides of the ridge or crease 13. When the trouser leg is then pressed by a hot iron or pressing machine, the ends 29 and 30 of the links are virtually cemented and vulcanized to the interior sides 15 and 16 at both sides of crease 13, while the intermediate linking strip or portion 31 of each link remains out of actual contact with the fabric. When the pressing operation has been performed so that both ends of the entire series of links 20 adhere to the inner sides of side portions 15 and 16 of the trouser leg adjacent the front crease 13, the strip 22 may be removed by pulling the same free of the links when the tension of the intermediate narrow portion 31 of the links will cause the sides 15 and 16 of the trouser leg to be brought more closely together, thus sharpening the angle of crease 13, as best seen in Figure 6.

The strip 22 may be supplied in sections of any practical length and proper lengths torn off from

the sections to correspond to the length of the crease to be retained or maintained thereby, and the links 20 may be made of natural or artificial rubber, plastic or any suitable material of an elastic nature, and which can be caused to adhere to the fabric to be creased, while the backing strip 22 may be made of paper, cardboard, fiber, or even plastic, if so desired.

Manifestly, variations may be resorted to and parts and features may be modified or used without others within the scope of the appended claims.

Having now fully described my invention, I claim:

15 1. A crease retaining device for garments comprising a backing strip having a fold line extending longitudinally intermediate the sides thereof, there being a first series of aligned spaced raised relief sections extending longitudinally of said backing strip on one side of the fold line of the latter, there being a second series of aligned spaced raised relief sections extending longitudinally of the backing strip on the other side of the fold line of the latter, the relief sections of said first and second series being in alignment with each other, the portions of said backing strip intermediate aligned opposed pairs of relief sections of said first and second series being depressed to thereby form transversely disposed recesses, and a link fabricated of elastic material extending between adjacent aligned opposed pairs of relief sections of said first and second series and having its end bearing against and temporarily secured to said sections with the connecting portion overlying the adjacent transverse recess.

2. A crease retaining device for garments comprising a backing strip having a fold line extending longitudinally intermediate the sides thereof, there being a first series of aligned spaced raised relief sections extending longitudinally of said backing strip on one side of the fold line of the latter, there being a second series of aligned spaced raised relief sections extending longitudinally of the backing strip on the other side of the fold line of the latter, the relief sections of said first and second series being in alignment with each other, the portions of said backing strip intermediate aligned opposed pairs of relief sections of said first and second series being depressed to thereby form transversely disposed recesses, and a link fabricated of elastic material extending between adjacent aligned opposed pairs of relief sections of said first and second series and having its end bearing against and temporarily secured to said sections with the connecting portion overlying the adjacent transverse recess, said backing strip being provided with a plurality of transversely disposed weakened lines, each of such lines extending between adjacent opposed pairs of raised sections of said first and second series.
